ELECTRIC HAMMER

Curtis Brown, Martinton, and William F. Parke,
Chicago, Ill.

Application October 17, 1946, Serial No. 703,790

4 Claims. (Cl. 153—32)

1

This invention relates to power hammers and more particularly to an electrically operated hammer for use in automobile body and fender work, riveting and the like.

One of the objects of this invention is the provision of a portable electrically operated hammer which is light in weight, which is easily manipulated and which requires comparatively little skill to operate.

Another object of this invention is the provision of an electrically operated hammer in which the frequency of the blows delivered by the hammer is comparatively high.

A further object of this invention is the provision of an electrically operated hammer in which the force of the blow delivered by the hammer may be adjusted to conform same to various types of work.

A still further object of this invention is the provision of an electrically operated hammer which can be swung around on its frame so that work may be done in restricted places.

More particularly, it is intended to provide a generally C-shaped frame carrying an opposed hammer and anvil at the upper and lower terminal, respectively, of the C, the frame being adjustably deformable for opening or closing the C, whereby the frame may be opened up for insertion of the hammer or anvil in close or cramped quarters. This, coupled with the arrangement for swinging the hammer with respect to the frame, is intended to provide for almost universal utility in the apparatus.

Another and further object is the provision of an electrically operated hammer which can be detached from its frame and used independently where a hammering action is required.

With the foregoing and other objects in view, the invention consists of a novel construction, combination and arrangement of parts as will be hereinafter more specifically described and illustrated in the accompanying drawings, wherein is disclosed an embodiment of the invention.

In the drawings—

Fig. 1 is an elevational view of my hammer and mounting as it would appear in use.

Fig. 2 is a view partially in cross section and partially in elevation of the hammer showing the hammering mechanism at the bottom of an operating stroke.

Fig. 3 is a similar view showing the hammering mechanism at the top of an operating stroke.

Fig. 4 is a vertical section taken on line 4—4 of Fig. 3.

Fig. 5 is a horizontal section taken on line 5—5 of Fig. 3.

Fig. 6 is a vertical section taken on line 6—6 of Fig. 2.

Fig. 7 is a horizontal section taken on line 7—7 of Fig. 2.

2

Fig. 8 is a vertical section taken on line 8—8 of Fig. 1.

Fig. 9 is an elevational view showing the hammer unit used independently of the frame.

In the embodiment of my invention as illustrated in the drawings, 10 indicates a housing which is adapted to contain the hammer and operating mechanism therefore, presently to be described. Said housing is substantially T-shaped and comprises a vertical tubular member 12 which forms the head of the T; and a horizontal member 14. The member 14 which forms the staff of the T terminates in an enlarged portion 15 which serves as part of the housing for the motor 16. Integrally formed with the housing 10 is a handle 17 which is adapted to house an electric switch 18.

Mounted on the enlarged portion 15 is an electric motor 16 which serves as the operating means for the hammer. A motor shaft 20 provided with a squared end portion 22 is journaled in a roller bearing 24 and extends into the tubular member 14. Mounted in bearings 26 and 27 in the tubular member 14 is a shaft 28 which is provided with a squared end portion 29. A coupling 30 receives the squared end portions 22 and 29 of the shafts 20 and 28 respectively and forms a driving connection between the motor shaft 20 and the shaft 28. A packing nut 34 is screwed into a threaded portion of the tubular member 14 and serves to retain the packing 33 around the shaft 28. A set screw 32 for securing the packing nut 34 in position and a grease fitting 35 are provided in the member 14. Mounted for rotation therewith on the shaft 28, intermediate of the bearings 26 and 27 is a worm 36 which is adapted to engage the pinion 38. Pinion 38 is mounted on a transverse shaft 40 which is journaled in roller bearings 42, 42. As shown in Figure 4, the bearings 42 are mounted in the web members 44 which screw into the opposite sides of the housing 10.

Mounted on the opposite sides of pinion 38 on the shaft 40 for rotation therewith is a pair of cams 46, 46 in alignment with each other. The cams 46 have oppositely positioned high portions, preferably 180° from each other, which, when rotated impart reciprocating movement to the hammer stem 48 in a manner presently to be described.

The hammer stem 48 is mounted for reciprocating movement in the vertical member 12 of the housing 10 which has a square shaped bore 49. The hammer stem comprises an upper portion 50 which is square in cross section and a lower cylindrical portion 52 formed integrally therewith. A shoulder 53 is formed at the junction of the portions 50 and 52, against which the cams 46 engage during operation of the hammer. The upper portion 50 is provided with a circular recess 54 which is adapted to serve as a seat for the

actuating spring 55. A longitudinal recess 56 in the square portion 50 serves to provide clearance for the worm gear 38.

A spring 58 is mounted in the member 12 and abuts, at its upper end, against a washer 59 which in turn rests against a shoulder 60 provided in the member 12, and at its lower end, against an externally threaded bushing designated 62 in Fig. 3 in threaded engagement with an internally threaded portion in the lower end of the member 12. The bushing 62 comprises two independent sections 62a and 62b, as shown in Fig. 2 having their opposed faces machined to provide a V-shaped recess to retain packing 63 therebetween. The hammer stem 48 is also provided with a reduced portion 65 which forms a shoulder 64 at the junction thereof with portion 52 and which is adapted to bear against the washer 59 and spring 58 during a portion of its downward travel thereby eliminating a considerable amount of the vibration usually attendant in the operation of such a device. The hammer head 66, provided with a socket 67 and set screw 68, is adapted to be secured on the end of the portion 65 of the hammer stem 48.

A knurled nut 69 provided with internal and external threads cooperates with the internally threaded portion of the member 12 and with the externally threaded spring adjusting sleeve 70. It will be seen that by means of the knurled knob 70' secured to the adjusting sleeve 70, the compression of the actuating spring 55 which abuts the under side of same can be easily adjusted. By regulating the compression of this spring the force of a blow required for a particular kind of work can be easily controlled by the operator.

Supporting the entire hammer unit is a horizontal tubular arm 73 having at one end a sleeve 74 positioned at right angles, and which serves as a continuation of the member 12. A bushing 75 is provided interiorly of sleeve 74 and is retained in position by a locking nut 76 which engages external threads at the upper portion of the sleeve. The lower portion of sleeve 74 is provided with internal threads which receive an externally threaded sleeve member 77 which serves as a guide for the hammer head 66. By threaded adjustment of sleeve member 77 upwardly and downwardly is sleeve 74, the gap between sleeve 77 and anvil 95 can be regulated, thus to regulate the effective bite of the hammer. It is thus apparent that when the hammer assembly is not otherwise held, that it may be freely swung in bushing 75 about the vertical axis of the hammer.

Locking means for maintaining the motor housing in rigid position are mounted on an upright standard 90 which forms part of the supporting frame 73, and comprises a slidably mounted pin 81 provided with a knob 82. The pin has a shoulder 83 against which a spring 84 too bears, and a suitable socket 85 in the end of the motor housing receives the pin. It will be seen by reference to the drawings that when the pin 81 is withdrawn from the socket 85 the motor housing can be swung around the vertical axis of the hammer stem 48 using the bushing 75 as a bearing surface. This arrangement is particularly desirable when work is being done in restricted places and where it is inconvenient to use the device in the rigid position shown in the drawings. The movement of the motor housing in this manner does not in any way effect the

positioning or operation of the hammering mechanism.

In Fig. 1 is shown a preferred form of frame for supporting the hammer and anvil, this frame being capable of being positioned in a vice or being used in a portable manner. The frame is generally C-shaped and comprises a horizontal arm 73 which forms the upper jaw of the C for supporting the motor 15 and hammer housing 10, and which is pivotally mounted as at 71' on a substantially U-shaped lower frame member 72, the free end of which forms the lower jaw of the C. The lower frame member is provided with lugs 78 which are adapted to receive a pin 79 for pivotally supporting an eye bolt 80.

The horizontal arm 73 is provided with a boss 86 which is angularly drilled to accommodate the eye bolt 80. A wing nut 87 on the eye bolt 80 serves to secure the frame members 72 and 73 in rigid relationship for operation.

As shown in Fig. 2 the free end of the lower frame member 72 is provided with a socket 88 and flange 89 for supporting an anvil member 91. While only one form of anvil has been illustrated 25 it will be understood that anvil members of different shapes and curvatures for shaping as well as for riveting may be used as required.

Because of the positioning of eye bolt 80 near the pivot point 71' of the two frame members 71 30 and 72 it will be seen that a very small longitudinal movement of the wing nut 87 on the eye bolt 80 will permit a comparatively wide separation of the frame members 72 and 73 at their free ends. The insertion of work between the hammer and 35 anvil, particularly that having a high degree of curvature is very easily accomplished with a minimum of adjustment.

The operation of the device is particularly simple, requiring very little experience on the 40 part of the operator. The wing nut 87 is unscrewed to separate the frame members 72 and 73 to permit the insertion of the work 95 therebetween and is thereafter tightened. When the 45 motor 16 is started by means of the switch 18 the worm is caused to rotate the worm gear 38 and cams 46 in a counter clockwise direction. The cams 46 engage the shoulder 53 of the hammer stem 48 and lift it upwardly against the compression of the spring 55. When the limit of upward travel is reached the cam 46 is freed from the shoulder 53 of the hammer stem 48 and the actuating spring 55 expands to force the hammer stem 48 downwardly, imparting a blow through 55 the hammer head 66. The hammer stem 48 in its downward travel tends to compress, to a very small degree, the spring 58 which serves to absorb some of the shock of the blow and thereby reduces vibration. As the cams 46 rotate the 60 hammer stem 48 is lifted up and the same cycle of operations just described follows through. The force of the blow is easily adjusted by turning the spring adjusting sleeve 70 to increase or decrease the compression of spring 55.

In cases where it is inconvenient to operate the device in the rigid form shown in Fig. 1, as where particular work areas are restricted or inaccessible, the pin 81 may be pulled out of the socket 85 and the motor housing may be horizontally 65 swung about a vertical axis without in any way affecting the operation of the hammer.

While the hammer unit is shown mounted on a frame and operating in cooperation therewith, it will be understood that the hammer unit may be removed from said frame and operated inde-

pendently thereof. When used in such a manner the unit 76 is unscrewed and the hammer unit slipped out of its support in the member 74. A sleeve 96 substantially of the same construction as the member 74 is positioned over the lower portion of the hammer unit and secured by the nut 76.

It is to be understood that the form of my invention, herewith shown and described, is to be taken as a preferred example of the same, and that various changes in the shape, size and arrangement of parts may be resorted to, without departing from the spirit of my invention, or the scope of the appended claims.

We claim:

1. A portable electric hammer comprising, in combination, a generally C-shaped frame including upper and lower jaw elements, an anvil on the free end of the lower jaw element, a hammer, a hammer motor, a driving connection between said hammer and hammer motor, and a generally T-shaped casing therefor, and including head and staff portions, the hammer having a working stroke across the gap of the C-shaped frame towards the anvil and being enclosed by the head portion, the motor and at least a portion of the driving connection being enclosed in said staff portion, means pivotally mounting said head portion on the free end of said upper jaw element for rotation about its longitudinal axis, the staff portion normally extending along the upper side of said upper jaw element a handle extending between said head and staff portions, and means releasably connecting the free end of said staff portion to said upper jaw element.

2. The combination claimed in claim 1, the last-named means comprising a lug extending upwardly from said upper jaw element, socket means on said staff portion, and a detent carried by said lug and releasably engageable in said socket means.

3. The combination claimed in claim 1, the means pivotally mounting said head portion on the free end of said upper jaw portion comprising, a sleeve affixed on the end of said upper jaw portion, the axis of said sleeve being directed towards said anvil, a bushing in said sleeve, a bearing on said head portion fitting in said bushing, and removable means for holding said bearing in said bushing, whereby said casing and the hammer, motor, and driving connection may be removed as a unit from said frame.

4. The combination claimed in claim 3, and a tubular hammer guide threadedly engaged on 10 that end of said sleeve which lies nearest said anvil whereby, upon threaded adjustment of said hammer guide, to alter the distance between the same and said anvil.

CURTIS BROWN.
WILLIAM F. PARKE.
